UNITED STATES PATENT OFFICE.

ROBERT RITTER VON PALLER, OF NUREMBERG, GERMANY.

STARTING DEVICE FOR EXPLOSIVE-ENGINES.

SPECIFICATION forming part of Letters Patent No. 655,269, dated August 7, 1900.

Application filed June 5, 1900. Serial No. 19,132. (No model.)

To all whom it may concern:

Be it known that I, ROBERT RITTER VON PALLER, a subject of the Emperor of Austria-Hungary, residing at 5 Gellertstrasse, Nuremberg, Germany, have invented Improvements 5 in Starting-Gear for Motor-Cars, of which the following is a specification.

This invention relates to a new or improved starting-gear capable of being readily and 10 conveniently actuated from the driver's seat. As compared with other gears designed for a similar purpose and consisting of more or less complicated coupling mechanism this gear differs by the extreme simplicity of its parts 15 and the peculiar manner in which they operate.

This starting-gear is operated by applying against the periphery of a pulley keyed on the driving-shaft of a motor-car a belt hanging 20 loosely when inoperative, and the two ends of which are provided with handles conveniently arranged within reach of the driver, this being effected by depressing, preferably by the foot, a treadle furnished with rollers 25 in such a manner that this driving-pulley, and hence the shaft, may be set in rotation in one direction or in the other, according to the handle which is pulled, while the belt returns to its former loose position as soon as 30 the treadle is released.

The accompanying drawings illustrate in side view the new starting-gear as fitted to a carriage-body.

The driving-pulley S is mounted on the 35 driving-shaft of the motor-car. Above this pulley S the roller o is fixed to the frame. Below the said pulley is arranged a lever h, fulcrumed to the base-plate of the carriage-body and having pivoted at one end a bar k, 40 carrying two rollers free to rotate thereon, while its other end carries a foot-plate f. Over the roller o and between the pulley S and the rollers m n runs the belt or strap r, which passes between the small guide-pulleys a and b, extends outside the carriage-body, and is provided at both ends with handles g' g². By 45 depressing the lever h with the foot and pulling the handle g' the bight of the belt or strap r is firmly pressed by the rollers m n against 50 the periphery of the pulley S and imparts thereto, and hence to the driving-shaft, a ro-

tation from the right to the left hand side, as indicated by the arrow. When the handle g² has reached a, the pressure is removed at f and the bolt or strap r, which is guided by the fixed roller o, is pulled loosely over the pulley S until it is drawn out at a. By now depressing again the treadle f and pulling anew the handle g' the motor is rotated again from the right to the left hand side, this manipulation being repeated until the motor is finally driven by the explosions.

Motors having a reversible gear can be driven backward from the left to the right hand side by pulling the handle g² instead of 60 the handle g'.

I claim—

1. A starting-gear for motor-cars, consisting of the combination with a pulley on the shaft of the motor, of a strap adjacent thereto, 70 with its ends arranged to be grasped by the operator, and means for pressing the bight of said strap against said pulley.

2. A starting-gear for motor-cars, consisting of the combination with a pulley on the 75 shaft of the motor, of a strap adjacent thereto, with its ends arranged to be grasped by the operator, and a lever arranged to press the bight of said strap against said pulley.

3. A starting-gear for motor-cars, consisting of the combination with a pulley on the shaft of the motor, of a strap adjacent thereto, with its ends arranged to be grasped by the operator, a lever, and a bar pivoted to said lever and carrying rollers adapted to press 85 the bight of said strap against said pulley.

4. A starting-gear for motor-cars, consisting of the combination with the pulley S on the shaft of the motor, of a fixed roller o adjacent thereto, a lever h having a footpiece 90 f and carrying a bar k provided with rollers m n, and a strap r having handles g' g² and passing between the pulley S and the rollers m n and around the roller o.

In witness whereof I have hereunto signed 95 my name, this 5th day of May, 1900, in the presence of two subscribing witnesses.

ROBERT RITTER VON PALLER.
